UNITED STATES PATENT OFFICE.

HANNAH JACOBS AND HARRY JACOBS, OF NEW YORK, N. Y.

HAIR WAVING AND CURLING DEVICE.

1,233,060.

Specification of Letters Patent. Patented July 10, 1917.

Application filed September 30, 1916. Serial No. 123,081.

To all whom it may concern:

Be it known that we, HANNAH JACOBS and HARRY JACOBS, citizens of the United States, and residents of New York city, in the county 5 of Kings and State of New York, have invented certain new and useful Improvements in Hair Waving and Curling Devices, of which the following is a specification.

This invention relates to an improved hair 10 waving or curling apparatus which is adapted to engage about a winding stem upon which the hair has been wound or curled and is in the nature of an improvement over a similar device for which our application 15 was filed on April 13, 1916; which application bears Serial Number 90,888 and was allowed on June 7th, 1916.

The object of this invention is to provide a device of the character described which 20 will accomplish the same purpose as that set forth in our said former application but which will be simpler in construction, more readily applied to use and be more economical in cost of manufacture.

25 We attain these objects by the device illustrated in the accompanying drawings in which Figure 1 is a side elevation of the completed device, Fig. 2 is an end view of same; Fig. 3 is a longitudinal section 30 through the device; Fig. 4 shows a front view of a cushion the function of which will be hereinafter explained; Fig. 5 is a section through the outer casing showing the internal members and cap removed and Fig. 6 is 35 a view of a portion of the device which will be hereinafter termed the drying chamber and which shows its members detached.

Referring to the parts 1 is a casing having a threaded portion 2 along the outer periphery of its open end 3, the opposite inner end, 4 of the casing 1 is formed with an inwardly 40 projecting portion, 5 which is adapted to engage a resilient washer or cushion 6, one side of which is formed with a concave surface 7 adapted to receive the base of a vacuum insulating member 8, the said cushion 6 is also formed with a cut out portion 9 providing a space for locating the sealing stem 10 of the said vacuum insulating member 8 45 affording thereby a protection for the said stem 10 against breakage from undue pressure when the parts are secured together. A central perforation 11 permits the said cushion 6 to engage over the inwardly projecting portion 5 of the said casing 1.

A heat insulating member 8 preferably a

double walled vacuum chamber, is adapted to engage within the casing 1 and against the cushion 6 as shown in Fig. 3 and is held snugly in place by a washer 12 which is in 60 turn held against the open end of the said insulating member 8 by an insulating plate 13.

The said insulating plate 13 is a part of a cap 14 threaded at its inner periphery 15 65 and adapted to engage with the threads 2 upon the casing 1. The said cap 14 is rigidly attached to the said insulating plate 13 at 16 and is formed with a circular knurled portion 17 provided to facilitate the 70 turning of said cap 14.

The said insulating plate 13 has a central threaded perforation 18 in which the threaded end 19 of a tube or drying chamber 20 is adapted to engage. 75

The said tube or drying chamber 20 is preferably made of copper and provided with a flange or shoulder 21 which is adapted to engage the washer 12 to hold same securely against the insulating plate 13. An 80 annular flange or ledge 22 is formed at the outer edge of the perforation 18 in insulating plate 13 to provide a stop for the edge 23 of the drying chamber 20.

The said cap 14 and its attached insulating plate 13, the washer 12 and the drying chamber 20 are secured together as a unit of the device and engage, by means of the threaded portions 15 and 2, upon and within the casing 1 and act to hold in place the 90 aforesaid insulating member 8 as indicated in Fig. 3. The parts are tightly screwed together so that sufficient pressure is brought upon the washer 12 by the edge of the insulating member 8 to make a water tight 95 joint between said washer and insulating member.

Grooves 24 are formed upon the said insulating plate 13 and are adapted to hold a sliding plate 25 which is made of any 100 suitable non-heat conducting material. Supporting eyes 26 are provided upon the casing 1 as shown.

In the application of this device to use, the hair is first wound, in the usual way 105 upon a stem and fastened thereon. The stem, with the hair upon it, is then inserted in the drying chamber 20; the said drying chamber 20 and its parts having first been attached to and within the casing 1. The 110 aforesaid insulating member 8 being also located within the casing 1 as shown in Fig.

3. Hot liquid, preferably water, is contained within the insulating member 8, between the inner wall of same and the wall of the drying chamber 20 and constitutes 5 the medium for supplying heat to the drying chamber 20; the insulating member 8 affording a means for confining the heat for the maximum length of time.

The slide 25 is provided to afford a means 10 for closing the aperture around the stem when the same is in position within the drying chamber and thereby prevents the rapid radiation of heat from the said drying chamber.

15 The washers 6 and 12 are made of resilient material preferably rubber.

It is obvious that we may embody various modifications without departing from the spirit of our invention; we do not therefore 20 wish to be understood as limiting ourselves to the particular construction shown.

What we do wish to secure by Letters Patent is—

25 In a hair waving and curling apparatus, a heat-insulating member adapted to con-

tain a liquid heating element, an outer jacket inclosing said liquid containing member, a drying member concentrically fastened to the said outer jacket and extending concentrically within the said liquid containing 30 member, a heat-insulating head or block securely fastened to the said drying member and detachably connected to the said outer jacket, a resilient washer or gasket held upon the said head and interposed between 35 it and edge of the liquid containing member, a resilient seat located within the said outer jacket and adapted to afford a base for the said liquid containing member and a means for closing the opening in said 40 head.

Signed at New York city, Brooklyn borough in the county of Kings and State of New York this 29th day of September A. D. 1916.

HANNAH JACOBS.
HARRY JACOBS.
